UNITED STATES PATENT OFFICE.

OSCAR B. BACH, OF NEW YORK, N. Y.

DESIGN FOR A SECRETARY.

Application filed April 5, 1927. Serial No. 21,460. Term of patent 3½ years.

To all whom it may concern:

Be it known that I, OSCAR B. BACH, a citizen of the United States, residing at New York city, in the county of New York and State of New York, have invented a new, original and ornamental Design for a Secretary, of which the following is a specification, reference being had to the accompanying drawing, forming part thereof, in which the figure is a view in perspective of a secretary showing my new design.

I claim—

The ornamental design for a secretary, as shown.

OSCAR B. BACH.
